Frederick O'Brien

UNITED STATES PATENT OFFICE.

FREDRIC C. WEIR, OF CINCINNATI, OHIO.

RAILROAD-CROSSING.

SPECIFICATION forming part of Letters Patent No. 249,707, dated November 15, 1881.

Application filed August 19, 1881. (No model.)

To all whom it may concern:

Be it known that I, FREDRIC C. WEIR, of Cincinnati, Hamilton county, State of Ohio, have invented an Improvement in Railroad-Crossings, of which the following is a specification.

My invention relates to that class of crossings which are constructed of rails.

Figure 1 is a plan of my invention. Fig. 2 is a sectional elevation on line $\alpha\alpha$, Fig. 1. Fig. 3 is a sectional elevation on line $\gamma\gamma$, Fig. 1. Fig. 4 is a sectional elevation on line $\zeta\zeta$, Fig. 1, with corner-piece removed. Fig. 5 is a sectional plan of one of the corners of the crossing, showing the arrangement of the angle-arm plates for strengthening the rails where cut away.

In constructing the crossing I use for the foundation, as it were, two rails, A A, of sufficient length to permit of notching the heads at the gage-width B of the track that is to cross it and reach outside of it at either side, enough to permit of the solid bent rail corner-strengthening pieces C and the fish-plates of the adjoining track D being fastened to them. These two rails I use for the track that has the greatest service over it. After notching at B these two rails, I provide wrought-iron angle-arm plates E, with the arms F projecting outwardly from them. These angle-arm plates E are sufficiently long to reach across the cut through the head of the rails, and are firmly riveted or bolted through the web G, thereby restoring as far as possible the loss of strength of material by the cutting away of the head of the rail to permit of the passage of the flanges of the wheels, and at the same time furnishing an angle-arm, F, to rivet or bolt to the intersecting pieces of rail, H, required to fill up and complete the crossing both inside and outside of these foundation-rails. The intersecting pieces of rails, H, required to complete the crossing of the two foundation-rails have their bases swaged upward at I and arranged to rest upon the top of the flanges of the two long or foundation rails, as shown in Figs. 1, 3, 4, and 5, thus making the long notched rails a foundation in fact. After having formed the body of the crossing in the manner above described and to the proper gage, I strengthen the structure by adding at the outside corners, as shown,

strengthening-angles C or J, or both, formed from the same-sized rail as the body of the crossing itself, and I likewise form inside continuous guard and additional strengthening angles, K, also formed from the same-sized rail, bent at two corners and joined at the two others by strengthening-plates L, the whole system of rails being held apart, where necessary, by spacing-blocks M and bolted through the several sections of rails, as shown. Where necessary to protect the throat or the openings into the crossings that are not guarded by bended corner rails, I use short guards that are spaced away from the main rails and bolted to the spacing-blocks.

The object of this invention is to provide a stronger and more durable crossing without the use of the base-plates frequently used, and thereby furnish through the additional strengthening-corners, inside as well as outside, a sufficiently broad bearing to enable the crossing to be laid on the ordinary ties, instead of the large and expensive timbers required in many cases, and, besides, making the crossing a more elastic portion of the road-bed than can be done with the use of plates under it.

It is obvious that different-sized rails from those used for the main tracks might be used; but the same size is preferable.

I have shown my improvement as applied to a right-angle crossing. It is obvious that it is equally adapted to any other required angle.

Having described my invention, what I claim is—

1. A railroad-crossing constructed of two rails of a length greater than the gage of the intersecting track, and having notches cut through the heads of said rails to permit the passage of the flanges of the wheels on said intersecting track, said rails being strengthened by angle-arm plates reaching by said notches on either one or both sides of said rails sufficiently to permit their being riveted or bolted to the webs of the said rails, substantially as specified.

2. A railroad-crossing constructed of two main rails notched through the heads to the gage of the track that is to cross it, and having its intersecting rails swaged upward, so that their bases shall rest on the top of the

flanges of the main rails, substantially as specified.

3. A railroad-crossing constructed of two main rails notched through the heads to the gage of the track that is to cross it, each of said rails having a strengthening-plate on one or both sides thereof at each notch, said plate having an arm-plate attached thereto and projecting therefrom at the required angle, to 10 which the intersecting rail is riveted or bolted, substantially as specified.

4. A railroad-crossing constructed of two main rails of a length greater than the gage of the intersecting track, and notched through

their heads to the gage of said intersecting track, and having its inside and outside corners strengthened by solidly-bent corners from the same material as the body of the crossing, said strengthening - corners also acting as guards, substantially as specified. 15 20

In testimony whereof I have hereunto set my hand in the presence of two subscribing witnesses.

FREDRIC C. WEIR.
